UNITED STATES PATENT OFFICE.

WILLIAM E. DAVIS, OF NEW IPSWICH, NEW HAMPSHIRE.

SCREW-DRIVER.

1,162,461.

Specification of Letters Patent.

Patented Nov. 30, 1915.

Application filed July 31, 1915. Serial No. 42,858.

To all whom it may concern:

Be it known that I, WILLIAM E. DAVIS, a citizen of the United States of America, and a resident of New Ipswich, county of Hillsborough, State of New Hampshire, have invented certain new and useful Improvements in Screw-Drivers, of which the following is a full and clear specification, reference being had to the accompanying drawings, in

10 which—

Figure 1 is a side elevation, partly in section, of a device embodying one form of my invention; Fig. 2 is a sectional view thereof on the line 2—2 of Fig. 1; Fig. 3 is a side elevation illustrating one manner of using my device; Fig. 4 is a section on the line 4—4 of Fig. 3; and Fig. 5 is a side elevation illustrating another embodiment of my invention.

20 The object of this invention is to provide a screw-driver having a plurality of different sized screw engaging blades, whereby the device may be, by a simple adjustment, readily adapted for driving screws of various sizes, as more fully hereinafter set forth.

In the drawing, *a* designates a bar longitudinally slotted at *b*, and in this slot is mounted a disk *c* having formed on its edge a series of different sized screw-driving 25 blades *d*, said disk being rotatively clamped in the slot *b* by means of a clamp screw *e* which passes through a central hole in the disk, the slot being just wide enough to enable the disk to be clamped tightly by a slight turn of the screw. With this construction, it will be observed that the bar *a* may be used as a handle which projects beyond the disk at diametrically opposite points and any one of the blades *d* may be 40 brought into convenient position for use.

To further lock the disk against rotation, I provide the disk with an annular series of holes *f* adapted to be engaged by a removable friction or other pin *g* inserted in a suitable hole *h* in one of the bifurcated parts of the handle, the inner end of the pin being adapted to enter a socket *i* in the opposite part of the handle bar. With this locking pin device, when the proper screw-driving edge is brought into the desired position, the locking pin is inserted and the disk will thereby be held against rotation during the handling of the tool. It will be understood, of course, that any suitable locking pin or other device may be used instead of the frictionally split pin shown.

To give the tool further utility, I may form on or attach to the opposite ends of the bar *a* other tools. In Figs. 1 and 2 I have shown at one end a screw-driver *j* which is adapted to be used in positions where no one of the blades *d* can be used, and at the other end of the bar I provide a gimlet counter-sink *k*. When either the tool *k* or *j* is in use, it is essential to cover and protect the opposite end of the bar so that it may be freely used without injuring the user. For this purpose, I provide a removable knob-like cap *l* which is adapted to frictionally fit over either end of the bar and inclose the tool at that end, an annular flange *m* being formed on the bar to form a stop against which the cap abuts. To prevent the cap rotating, I provide the flange *m* with a lug *n* which interlocks with the edge of the cap. In Fig. 5 I show what may be termed the simplest embodiment of my invention, the tools *j* and *k* being omitted and the bar being bowed to form a better handle.

It is desirable at times to enable the screw-drivers *d* to be used with a longer handle than is afforded when they are used as shown in Figs. 1 and 2. To enable this to be done, at a point at one side of the disk, I provide a joint in the bar *a*. In the present instance I have shown a screw joint which consists of an internally threaded socket *o* and an externally threaded screw *p*, this screw *p* being longitudinally divided by an extension of the slot *b*. By unscrewing the part of the bar carrying the socket *o* and by removing the clamp screw *e* and the pin *g*, the disk *c* may be adjusted to the position shown in Fig. 3, in which position each one of its drivers *d* may be rotated to a position where it will extend beyond the adjacent end of the remaining part of the main bar *a*, the sectional construction of the screw *p* permitting the disk to be forced outwardly between the parts thereof, the bifurcated parts of the handle being sufficiently resilient to permit this to be done. To hold the disk in this advanced position, the pin *g* will be inserted in the holes in the bar formerly occupied by the clamp screw and the clamp screw will be inserted in the holes in the bar formerly occupied by the pin, the pin socket *i* being internally threaded for the reception of the inner end of the clamp screw where that type of clamp screw is employed.

It will be observed that numerous modifi-

cations as to the details of my device may be made without departing from the spirit of my invention.

Having thus described my invention, what I claim is:

- 5 1. A screw driver of the class described, consisting of a bar provided with a longitudinal slot about midway its length, the bar being provided with a separable joint at one 10 end of said slot, a disk carrying at its edge a plurality of different-sized screw drivers and means whereby the disk is held rotatively either in the center of the slot or at one end thereof, means being provided for 15 holding the disk against rotation in each of its positions, the proportions of the parts

being such that when the disk is located at the end of the slot and the end section of the bar is detached at least one of the screw drivers on the disk will project beyond the 20 end of the bar.

2. A screw driver consisting of a bar provided with a longitudinal slot midway its length, a disk journaled in said slot, and means for locking this disk in different rotative positions, said disk being provided on its edge with a plurality of different-sized screw drivers.

In testimony whereof I hereunto affix my signature.

WILLIAM E. DAVIS.
